JOSEPH M. MERROW, OF HARTFORD, CONNECTICUT, ASSIGNOR TO THE MERROW MACHINE COMPANY, OF HARTFORD, CONNECTICUT, A CORPORATION OF CONNECTICUT.

SEWING-MACHINE.

1,243,089.

Specification of Letters Patent. Patented Oct. 16, 1917.

Application filed October 19, 1915. Serial No. 56,700.

To all whom it may concern:

Be it known that I, JOSEPH M. MERROW, a citizen of the United States, residing at Hartford, in the county of Hartford, State 5 of Connecticut, have invented certain new and useful Improvements in Sewing-Machines; and I do hereby declare the following to be a full, clear, and exact description of the same, reference being had 10 to the accompanying drawings, forming a part of this specification, and to the figures and letters of reference thereon.

This invention relates to mechanism for facilitating the stitching of circular work. 15 As an example of such work, pads employed for applying cosmetics may be cited. These pads are made up of disks of soft leather, as chamois, preferably secured together at their edges by overstitching. It is highly 20 desirable that the finish thus provided be neat and attractive in appearance and effected at a speed impracticable to attain without special appliances. The provision 25 of such appliances is primarily the object of my invention, which as will hereinafter appear possesses many features of advantage each in itself a further attained object.

In the drawings accompanying and forming a part of the present specification I have 30 shown in detail and in connection with a Merrow overstitching machine one convenient form of embodiment of my invention. It is to be understood, however, that any 35 suitable type of stitching mechanism may be substituted for that shown and described, although overseaming mechanism is considered desirable and the latter is believed to be most useful for the particular work herein set forth.

40 Referring to the drawings:

Figure 1 is a front view of a Merrow overstitching machine embodying the present invention, certain of the parts being shown in section and the work showing in section 45 on line 1—1 of Fig. 2.

Fig. 2, is a plan view of the work plate and needle plate of the machine shown in Fig. 1, together with other adjacent parts.

Fig. 3, is a sectional view on line 3—3 of 50 Fig. 2 and,

Fig. 4, is an end view of the machine with certain parts swung to a different position from that in which they are shown in Fig. 1.

Similar characters of reference designate

similar parts throughout the several views of the drawings.

Briefly describing the machine with respect to that part of the construction which is familiar to those cognizant of the sewing machine art, the numeral 1 designates a curved oscillatory eye pointed needle, 2 a lower looper, and 3 an upper looper.

The lower looper 2, is rigidly secured in a slide 4, supported in a guideway 5, on the inner face of a cap 6, which is fitted 65 into a side opening of the machine frame. Pivottally carried by said slide is a carrier 8, for the upper looper 2, said carrier having laterally extending arms 9 and 10, provided with roll bearing studs 11 and 12, adapted 70 respectively to enter grooves 13 and 14, in cam cylinders 15 and 16, supported by shafts 17 and 18. Gears 19 and 20, connect the two cam cylinders which are secured by set screws 21 and 22, to their respective shafts, 75 so that when the driving shaft 17, is rotated the cam cylinders and shaft 18, will rotate in unison therewith. As said cam cylinders rotate the correlated grooves there-in move the arms 9 and 10. This motion of 80 said arms, transmitted through the upper looper carrier and slide 4, causes looper 2, to reciprocate below the needle plate, and looper 3, to reciprocate and oscillate so that it passes above and below the needle plate, 85 in a curved path extending around one edge thereof. The needle moves to coöperate with the lower looper below the needle plate and with the upper looper above the needle plate, and the loopers move to coöperate 90 with each other below the plane of the needle plate, all in accordance with a well known method of forming overedge stitches. The needle receives its motion through the link 23, which connects the needle carrier 24, 95 with an eccentric projection 25, at the end of shaft 18.

Mechanism comprising the present invention as associated with the stitch forming mechanism briefly set forth above will now 100 be described.

Supported by a flanged lug 30, projecting from the machine frame 7, is a work plate carrier 31, to which is secured by screws 32, the work plate proper 33. Passing through 105 these two last mentioned members and serving to hold them for swinging motion upon their support, is a headed pivot pin

34, clamped against longitudinal movement by a set screw 34'. As shown it will be observed that said pivot 34, also serves as a hinge pin for the member 35, which is 5 a cover or guard for feed mechanism (not herein shown as it constitutes no part of the present invention.) In order to freely support the work (as the pad 36) for turning movement, a turntable 37, is provided, comprising a disk having a shank 38, journaled in a bearing 39, of the bracket 40, which is secured to the underside of the work plate by screws 41. The upper surface of disk 37, is flush with the like surfaces of 10 the work plate and needle plate, so that when the work plate is swung to the position in which it is shown in Figs. 1 and 2, the surfaces of all of said members are effective for supporting the work. The work plate 15 is cut away to accommodate the turntable, and also, on that side which is toward the needle plate, it is shaped to conform to the latter. Secured to the work plate at that side of the turntable opposite to the needle 20 plate, is a locating member 45, which comprises a plate having a semi-circular recess 46, which forms a guide by which to centralize the work upon the turntable. That 25 it may accommodate different sizes of work, this guide member is adjustable. Also it is 30 provided with a curved projection 47, by which the work plate and associated parts may be conveniently positioned as required.

For reasons that will become hereinafter 35 more fully apparent, it is desirable to maintain the work in fixed relation to the turntable, and clamping means for the purpose will now be described. The work plate carrier 31, is provided with a boss 50, tapped 40 to receive the screw stud 51, which pivotally supports the L-shaped arm 52. Riveted or otherwise secured to the free end of this arm 52, is a cylindrical head 53, formed with a button 54, at one end and reduced 45 to form a round pointed pin 55, at the other end. A clamp disk 56, having a shank 57, is provided with a bore 58, to very freely receive the pin 55, the rounded point of the latter being adapted to engage 50 the bottom of the bore and press the clamp disk against the work, said disk at the same time being perfectly free to turn with the work clamped between it and the turntable. Oppositely disposed halves 59 and 60, of an 55 inwardly flanged thimble-shaped member are secured as by screws 61, to the head 53, with the flange 62, in engagement with an annular groove 64, in the clamp disk shank. The relative position of said flange 62, 60 length of pin 55, depth of bore 58, and width of groove 64, obviously insure confinement of effective pressure contact upon the disk, to the rounded point of the pin and bottom of the bore. Such contact is desirable, in- 65asmuch as it permits the clamp disk, as be-

fore intimated, to automatically adjust itself into parallelism with the work, when the latter is clamped between said disk and the turntable, irrespective of the thickness of the work and the fact that it may be 70 thicker at one side than at the other. The upper surface of clamp disk 56, is fluted as at 56', or otherwise roughened, to afford a convenient hold, by which said clamp may be rotated by the operator, to initially move 75 the work into proper position with respect to the stitching mechanism. As will have been inferred, the L-shaped arm 52, is manually movable about its pivot, to permit the clamp disk to be moved into a position adjacent to the work plate, as shown in Figs. 1 and 2, or away from the work plate, as shown in Fig. 4. It is convenient to have this arm frictionally held at its pivotal joint, so that it will slightly resist displacement from the various positions to which it is adjustable. A friction washer as 66, of leather or other suitable material, introduced under the head of screw stud 51, accomplishes this end, and, for present purposes, is found more useful and convenient than a spring acting upon the arm. The degree of friction exerted upon said arm, may be regulated by adjusting the screw stud, which latter may be held in a desired 95 adjustment by a set screw, as 67, tapped into the boss 50.

When in clamping relations, the clamp disk 56, is axially aligned with the turntable 37, so that these two members, together with 100 the work firmly secured between them, are perfectly free to be rotated by feed devices, to advance the peripheral margin of the work to the stitching mechanism.

In connection with the feed dog 68, which 105 operates in the usual way through the needle plate, I prefer to use a rotary or wheel presser foot as illustrated. Such a device forms the subject of United States Patent #1,001,388 granted to H. B. Gould, August 22nd, 1911, and therefore need not here be 110 described at length. It will suffice to state, that the presser foot 70, which has a small work engaging area, co-active with the needle plate to prevent backward movement of said 115 work during retraction of the feed dog, and to facilitate the control of the edge of the work, is supplemented by an axially inclined peripherally serrated wheel 71, which holds the work, without stretching or buckling effect, against the feed dog during the advancing movement of the latter. Both the presser foot and wheel, are carried at the end of the usual presser bar 73, and are normally forced toward the needle plate, 120 by a spring as 74. A lifter lever 75, for raising the presser bar to permit of work being introduced under the wheel and presser foot, is pivoted at 76, to the head cap 77. One arm 78, of said lifter is adapt- 125 130

ed to engage a pin 79, projecting from the presser bar through a slot 80, in the head cap 77, while another arm 81, is suitably extended to receive a cord, or chain (not shown) by which the lifter may be operated, in a direction to lift the presser bar, as by foot power. Movement of said lever in the opposite direction, is imparted by a spring 82, secured at its ends to ears 83, and 84, 5 extending respectively from lever 75, and head cap 77. Normally this spring maintains the lever in the position in which it is shown in Fig. 5. Thus held, it permits freedom for that movement of the presser bar which is effected by the feed dog. In order to confine the movement of lever 75, to limits within which it is desirably effective, it is provided with a pin 86, which projects into a slot 87, in the head cap. 10

20 In Figs. 1 and 2, I have illustrated for trimming the work, mechanism commonly employed in connection with the type of machine shown. Such mechanism, which is operated in a well known manner, includes the lower cutter 90, and upper cutter 91, which cutters operate to trim the work adjacent to one side of the needle plate, slightly in advance of the needle. Both cutters are adjustable in the usual manner, 25 so that the line of trimming, or distance of the cutters from the line of needle penetration, may be varied. Should it be desirable to vary the line of needle penetration, with respect to the center of the work, the stop screw 93, may be adjusted, said screw being threaded into the bracket 40, and adapted at its point, to bear against the needle plate support, to thereby limit the inward swing 30 of the work. 35

40 Control over the positioning of the work plate, is facilitated by introducing a spring backed plunger as 95, beneath the work plate carrier. The plunger is forced against said carrier, with sufficient pressure to prevent objectionable freedom of movement 45 thereof together with the work plate, about the pivot 34. Furthermore the plunger, acting as a detent, to enter slight depressions, as 96, in the under surface of the carrier, 50 serves to prevent accidental displacement of the latter and the work plate carried thereby, from adjusted positions, or in other words, from the position occupied when work is placed upon the work plate, or that 55 occupied when the stitching is being performed.

Referring again to the needle plate, attention is directed to the inclined lip 97, depending therefrom, the purpose of which is 60 to deflect upwardly on to the needle plate, that portion of the work which is unsupported by the work plate and the turntable. This deflecting action occurs when the work 65 is being swung into position for stitching. The method of using the pad stitching 70

mechanism is as follows:—Assuming the work plate and clamp disk to have been swung to the positions in which they are shown in Fig. 4, the operator places the work upon the work plate, in approximate 75 concentricity with the turntable, the locating member having been previously adjusted to unmistakably define the proper position for the particular diameter of work to be stitched. The clamp disk is next moved by 80 hand pressure, applied at the button 54, into clamping relation to hold the work firmly upon the turntable. The presser wheel and foot being next raised by foot power, the work plate and associated parts are swung 85 toward the needle plate. If the edge of the work, where it is unsupported by the work plate and turntable, happens to sag, it will, on approaching the needle plate, be engaged by the inclined lip 97, and finally deflected 90 thereby, upwardly on to the said needle plate. As the regulating screw 93, engages the needle plate support, the work plate will have passed the work under the presser wheel and foot, to a position where the extreme edge thereof, will extend between the trimming cutters an amount equal to that which is to be trimmed from the edge of the pad. During the final positioning of 95 the work plate in proximity to the stitching mechanism, rotation of the work, tends to facilitate the passage of its edge under the presser wheel and foot. Rotation of the work, for this purpose, may be readily effected, as already implied, by pressing 100 obliquely against the roughened upper surface of the clamp disk with a finger of the same hand which controls both the adjusting of said clamp, and positioning of the work plate, thus promoting convenience. 105

Having completed the above noted operations for properly locating the work, the presser wheel and foot, may be lowered, and the machine set in motion to perform feeding, trimming and stitching. When stitches have been applied throughout the desired extent of the periphery of the work, the latter may be guided away from the feeding, 110 trimming and stitching mechanism, after swinging the work plate slightly to the left 115 (as seen in Fig. 2).

Having thus described my invention, what I claim is,

1. In a sewing machine, the combination with stitch forming mechanism, of a needle plate, a work plate mounted for movement in a plane substantially coincident with that of the needle plate, a turntable carried by the work plate, an arm pivoted to the work plate, and a rotatable disk carried by the 120 arm for bodily movement toward and from the turntable.
2. In a sewing machine, the combination with stitch forming mechanism, of a needle plate, a work plate, a turntable supported 125

4

by the work plate, each of said devices having a work engaging surface substantially coincident with a single plane, and supporting means for the work plate adapted to permit of movement in said plane of the work plate and turntable.

3. In a sewing machine, the combination with stitch forming mechanism, of a needle plate, a work plate having an opening in its 10 work engaging surface, a turntable in said opening, supported by the work plate below the work engaging surface thereof, an arm carried by the work plate, clamping means associated with the arm above the turntable 15 and a support for the work plate adapted to permit of its movement toward and from the needle plate.

4. In a sewing machine the combination with stitch forming mechanism of a movable 20 work support, a turntable carried by the work support, a disk coöperative with the turntable to clamp the work, an adjustable arm for carrying the disk, and means for connecting said arm and disk for universal 25 movement therebetween.

5. In a sewing machine, the combination with stitch forming mechanism, of a needle plate, a movable work support, and pivotal work clamping means associated with the

work support, each of said devices having a work engaging surface substantially in a single plane, and the needle plate having an inclined lip leading to its work supporting surface, whereby an edge of material held by the clamping means will be deflected to 35 said needle plate supporting surface as the work support is moved toward the stitch forming mechanism.

6. In a sewing machine, the combination with stitch forming mechanism and work 40 feeding mechanism including a feed dog and presser foot, of a work support movable bodily toward and from the stitch forming and work-feeding mechanism in the plane of the work, said work support embodying a 45 turntable free to rotate as the work is fed and a freely rotatable clamp movable axially toward and from the turntable and connected with the turntable for movement toward and from the feeding mechanism by 50 supporting connections located at one side of the axis of the turntable and clamp and beyond the periphery of the work.

JOSEPH M. MERROW.
